CLAIM

The ornamental design for a bottle, as shown and described.

DESCRIPTION

FIG. 1 is a front perspective view from above and to one side of the bottles showing the new design.

FIG. 2 is a front view of the bottle of FIG. 1.

FIG. 3 is a rear view of the bottle of FIG. 1.

FIG. 4 is a right side view of the bottle of FIG. 1, the left side being a mirror image thereof.

FIG. 5 is a top plan view of the bottle of FIG. 1; and,

FIG. 6 is a bottom plan view of the bottle of FIG. 1.

The broken line showing in FIG. 3 is for illustrative purposes only and forms no part of the claimed design.

1 Claim, 1 Drawing Sheet

Matter enclosed in heavy brackets [ ] appears in the original patent, but forms no part of this reissue; matter printed in italics indicates the additions made by reissue.
